US00D761960S

(12) **United States Design Patent**
Petersen et al.

(10) **Patent No.:** **US D761,960 S**
(45) **Date of Patent:** **** Jul. 19, 2016**

(54) **AIMING DEVICE**

(71) Applicants: **Wolf Petersen**, Berlin (DE); **Michael Raschke**, Münster (DE); **Steffen Schanz**, Rottweil (DE); **Annika Müller**, Geislingen (DE)

(72) Inventors: **Wolf Petersen**, Berlin (DE); **Michael Raschke**, Münster (DE); **Steffen Schanz**, Rottweil (DE); **Annika Müller**, Geislingen (DE)

(73) Assignee: **Karl Storz GmbH & Co. KG**, Tuttlingen (DE)

(**) Term: **14 Years**

(21) Appl. No.: **29/526,261**

(22) Filed: **May 7, 2015**

(30) **Foreign Application Priority Data**

Nov. 7, 2014 (EM) 002574020-0001

(51) LOC (10) Cl. **24-02**

(57) **CLAIM**

The ornamental design for an aiming device, as shown and described.

DESCRIPTION

FIG. 1 is a rear left side isometric view of an aiming device in accordance with the new design;

FIG. 2 is a left side view thereof;

FIG. 3 is a right side view thereof;

FIG. 4 is a rear elevational view thereof;

FIG. 5 is a front elevational view thereof;

FIG. 6 is a top plan view thereof; and,

FIG. 7 is a bottom plan view thereof.

The broken lines shown in FIG. 7 are for the purpose of illustrating portions of the aiming device that form no part of the claimed design.

1 Claim, 7 Drawing Sheets
